TIMER CONTROLLED DUAL THERMOSTAT

Walter A. Cross, R.D. 1, Box 203E, Rte. 88,
Bristolville, Ohio 44402

Filed Sept. 27, 1973, Ser. No. 401,193

Term of patent 14 years

Int. Cl. D10—04

U.S. Cl. D10—51

FIG. 1 is a front elevational view of a timer controlled dual thermostat showing my new design, the rear being substantially plain and unornamented;

FIG. 2 is a side elevational view as taken from line 2—2 of FIG. 1;

FIG. 3 is a side elevational view as taken from line 3—3 of FIG. 1;

FIG. 4 is a top plan view thereof, the bottom plan being plain and unornamented.

I claim:

The ornamental design for a timer controlled dual thermostat, substantially as shown and described.
